UNITED STATES PATENT OFFICE.

GEORGE A. TUCK, OF SAN FRANCISCO, CALIFORNIA.

AUTOMATIC GAS CONTROL.

Application filed March 2, 1923. Serial No. 622,421.

To all whom it may concern:

Be it known that I, GEORGE A. TUCK, a citizen of the United States, residing in the city and county of San Francisco and State of California, have invented a new and useful Improvement in Automatic Gas Controls, of which the following is a specification.

My invention relates to improvements in automatic cut-offs for gas burners and the like wherein a pilot burner is connected with a cut off valve and arranged to normally maintain said valve open while the pilot flame is burning, and to close said valve should the pilot flame become extinguished.

The primary object of my invention is to provide an improved automatic cut-off for gas burners.

20 A further object is to provide a device which may be readily installed in connection with gas burners of various descriptions.

25 A further object is to provide an improved arrangement whereby the gas control may be readily set in an open condition and rigidly maintained in such condition so long as the pilot light is burning.

Another object is to provide an improved 30 construction which may be readily adjusted to compensate for wear.

A still further object is to provide an improved construction which may be cheaply constructed and which may be connected with existing installations with a 35 minimum of labor and expense.

I accomplish these and other objects by means disclosed in the drawings forming a part of the present specification wherein like 40 characters of reference are used to designate similar parts throughout the said specification and drawings and in which—

Fig. 1 is a broken front elevation partly in vertical section of one form of gas 45 burner, showing the application of my improved pilot light in connection therewith.

Fig. 2 is a broken side elevation of my improved pilot burner showing the connection with a cut-off valve and the operation 50 thereof when the gas is extinguished.

Fig. 3 is an enlarged detail of the valve securing means.

Fig. 4 is a broken detail partly in vertical section showing the lower portion of the

pilot light as viewed from the right of 55 Fig. 2.

Gas burners which are operated in connection with heating system, hot water heaters, and many other devices wherein the main burner is more or less frequently 60 turned on and off, are commonly equipped with a pilot burner connected with the gas supply and arranged to burn a small jet of gas at all times, said pilot burner being mounted in relatively close proximity to the 65 main burner and the jet directed thereover so that as soon as the gas is turned on the gas issuing from the burner will be ignited. However, as the gas frequently collects above the burner in sufficient quantity to 70 cause a slight explosion when ignited, it often happens that the pilot flame is extinguished. Thus when the burner is turned off and later again turned on, the flame of the pilot burner having been extinguished, 75 the gas issuing from the burner will not be ignited and as a result the inflammable gas will collect in and around the burner to an extent greatly endangering life and property. 80

To insure against this danger I have provided an improved device wherein the pilot burner normally operates in the usual manner to ignite the gas issuing from the burner, but is characterized by the provision of means for automatically cutting off the gas supply to the main burner should the pilot flame be inadvertently extinguished. 85

Referring particularly to the drawings my 90 invention will be seen to consist of a pilot burner formed from a tubular member 1, mounted within a gas heating device 2 provided with a gas burner 3, of any suitable character to which gas is fed through a supply conduit 4. A flanged cap 6 is threaded or otherwise secured upon the upper end of the tubular member 1, said cap having radially disposed apertures 7 formed immediately below the flange. A rod 8 is secured 95 at one end to the cap 6, preferably by threading into a suitable threaded aperture formed in the top of said cap, said rod extending through the tubular member. 100

The end of the tubular member 1 opposite 105 the cap 6 is provided with a suitable fitting 9, having an opening 10 arranged to receive an apertured plug 11, forming a close slid-

ing fit with the rod 8 which is extended outwardly therethrough. An opening 12 in the side of the fitting 9, is arranged to receive a fitting 13 to which is connected one end of a conduit 14. The other end of the conduit 14 is connected through a suitable gas cock 16 with the supply conduit 4 whereby gas is directed from said supply conduit to the tubular member, said gas issuing from the apertures 7 and burning in a manner herein-after more fully described.

A valve 17 is mounted in connection with the supply conduit 4 between the cock 16 and the main burner 3 to control the passage 15 of gas to said burner 3. The valve 17, is entirely independent of the usual burner control valve 20 and may be of any standard construction, a type wherein a lever 18 mounted upon a lateral extension is arranged to actuate a closing member within the valve being shown in the drawings by way of illustration, but as the mechanism of the valve forms no part of the present invention a detailed illustration or description 20 is omitted.

A slotted member 19 is slidably mounted upon the outwardly extending end of the rod 8, said member 19 being arranged to be normally held against the outer end of the plug 11 by means of a clamping member 21, mounted upon the outer end of the rod 8, and having a slight pivotal movement thereof. The clamping member 21, is held upon the rod 8, by means of a nut 22, a washer 23 being mounted between the nut and the member 21, to provide an adequate bearing surface for the clamping member, and a retaining nut 24 threaded onto the end of the rod 8, to retain the nut 22 in a desired position 30 upon the rod. The member 19 is apertured at one end thereof to receive one end of a connection 26 secured between the lever 18 and said slide member 19. The lever 18 is provided with a weight 27 arranged to be 40 actuated by gravity to move the lever to a closing position. The lever 18 is normally held in an open position by means of the connection 26, the slide member being held against the plug 11 by the clamping member 21, after said slide member has been moved to a position causing the lever 18 to be moved to a desired elevation.

The tubular member 1 above described is made of suitable material having a high coefficient of expansion. The rod 8 is made of material having a lower coefficient of expansion than that of the tubular member so that when the two are heated a greater expansion will occur in the tubular member 50 than in the rod. In practice I find that by making a tubular member of brass and the rod of steel a satisfactory result is obtained, but other metals or alloys may be of course substituted if desired.

60 The pilot burner is initially adjusted

while cool by means of the nut 22 which is moved to such a position that a cam surface 25 formed upon the clamping member 21 will engage the under surface of the member 19 and hold said member 19 lightly against 70 the lower end of the tube 1 or plug 11, but not with sufficient pressure to resist the pull of the weighted lever 18 against the member 19. The clamping element 21 is provided with a handle portion 28 by which it may be 75 pivotally moved upon a fulcrum point 29 whereby the cam surface may be caused to release all pressure against the member 19.

In operation my invention is as follows. The pilot burner being mounted in any suitable manner in connection with the supply pipe and adjusted as above described, the cock 16 is opened and the gas, which will then issue from the apertures 7, ignited. The heat of this burning gas issuing directly below the flange of the cap 6 will cause said cap to quickly become heated, the conductivity of the metal causing heat to be imparted to the tubular member 1 and to the rod 8. As the member 1 and 8 become heated an expansion will occur. The tubular member, having the greater coefficient of expansion, will expand a greater amount than the rod 8, the difference in expansion of these two members causing the clamping element 21 to be drawn tightly against the member 19 which is thereby rigidly clamped against the lower end of the tubular member. 90

100 After the pilot burner has been allowed to burn sufficiently long to thoroughly heat the burner, the weighted lever 18 is elevated to open the valve 17, and the member 19, moved along the rod 8 until the connection 26 is drawn tight, the clamping element 21 being previously moved to the position shown in full lines in Fig. 3 to permit free movement of the member 19 to the desired position. The clamping element is then moved by means of the handle portion 28 to the position shown in dotted lines in Fig. 3, thereby 105 causing a clamping pressure to be applied against the member 19 which member and the valve lever 18 are thereby maintained in the normal operative position shown in full lines in Fig. 2. So long as the pilot burner remains lighted and the members thereby 110 maintained in their heat expanded condition, the member 19 will remain clamped in position and the burners will operate in the well known manner. However, should the pilot flame become extinguished, the tube 1, and rod 8 will immediately begin to cool and as soon as the resulting contraction causes the members to return to their normal condition 115

120 the pressure caused by their unequal expansion will be relieved and the weighted lever 18 thus permitted to drop to a valve closing position, as shown in dotted lines in Fig. 2, thereby closing the cut-off valve 17 and pre- 125 130

venting the passage of further quantities of gas to the burner 3.

It is thus seen that so long as the pilot burner is lighted the main burner 3 can be controlled by a thermostatic or other character of control valve 20 in the usual manner, but when the pilot burner is extinguished the supply is cut off entirely independently of such valve 20 and the escape of gas prevented in the event the burner control valve is opened before the pilot is again lighted and the cut-off valve 17 reset in the manner above described.

The cut-off valve 17 may be closed while the pilot burner is burning by manually moving the clamping element 21 to release the pressure upon the element 19, the throw of the cam surface 25 when the element is moved to the position shown in full lines in Fig. 3 being sufficient to cause the member 19 to be disengaged even when the tubular member and the rod 8 are fully expanded by heat.

The precise construction and relation of parts above described is of course subject to modification in a great number of ways to conform to the requirements of different types of burners and burner installations. I therefore do not desire to restrict myself closely to precise disclosure herein contained, but wish to avail myself of such modifications as may fall within the scope of the appended claims.

Having thus described my invention what I claim as new and desire to secure by Letters Patent is:

1. The combination with a gas burner, a supply pipe, and cut-off valve mounted in the supply pipe for controlling the flow of gas through the pipe to the burner, of a pilot burner mounted adjacent the burner, said pilot comprising a tubular member connected to the supply pipe and having an opening arranged to direct a jet of burning gas over the burner; a rod extending through the tubular member, said rod being secured in one end of the tubular member and slidably engaged at the other end thereof; a member slidably mounted upon the rod, said member being connected to the cut-off valve; and means mounted upon one end of the rod for clamping said sliding member against the tube to maintain the valve in open position when the tube and rod are expanded by the heat of the burning flame, said means being arranged to release said slide member when the members contract upon cooling of the parts thereof when the pilot flame is extinguished.

2. The combination with a gas burner, supply pipe, and cut-off valve mounted in the supply pipe for controlling the flow of gas through the pipe to the burner, of a pilot burner mounted adjacent the burner, said pilot burner comprising a tubular member connected to the supply pipe and

having an opening arranged to direct a jet of burning gas over the burner; a rod extending through the tubular member, said rod being secured within one end of said tubular member and extending through the other end of said outward member and in sliding engagement therewith; a member slidably mounted within the burner and upon the outwardly extending end of said rod and connected to the cut-off valve; and adjustable means mounted upon the outer end of the rod and actuated by unequal expansion of the rod and of the tubular member when heated by the burning jet, for clamping said slide member against the tubular member to normally retain the cut-off valve in an open position and to automatically release said slide member when the tubular member and rod are contracted upon cooling after the pilot flame is extinguished.

3. The combination with a gas burner supply pipe, and cut-off valve mounted in said supply pipe for controlling the flow of gas through the pipe to the burner, of a pilot burner mounted adjacent the burner, said pilot burner comprising a tubular member arranged to direct a jet of burning gas over the burner; a rod extending through the tubular member, said rod being secured within one end of the tubular member and extending outwardly through the other end of the said member and in slidable engagement therewith; a slotted member slidably mounted upon the outer end of the rod and connected to the valve; a clamping member mounted upon the rod; and means mounted upon the outer end of said rod for holding the clamping member in proximate relation to the slotted member, said slotted member being slidable between the clamping member and the end of the tubular member when the rod and tubular member are cool and rigidly clamped between the clamping member and the tubular member due to unequal expansion of said rod and tubular member, when heated by the burning jet, whereby the valve may be maintained in open position while the pilot is burning and released to a closed position when the pilot is extinguished.

4. The combination with a gas burner, supply pipe and gravity actuated cut-off valve, mounted in the supply pipe for controlling the flow therethrough to the burner, of a pilot burner mounted adjacent the burner, said pilot burner comprising a tubular member; a cap secured upon one end of the tubular member and apertured to direct burning gas therefrom over the burner; a rod extending through the tubular member, said rod being secured at one end upon the cap and extending outwardly through the opposite end of the tubular member in slideable engagement therewith, the rod and tubular members being made of metals

adapted to cause a greater expansion of the tubular member than of the rod when heated by the burning jet; a slotted member slidably mounted upon the rod adjacent the 5 end of the tubular member and connected to the cut-off valve; a clamping member slidably pivotally mounted upon the rod adjacent the slotted member; nuts threaded onto the outer end of the rod for adjust- 10 ably holding the clamping member in proximate relation to the slotted member, said slotted member being rigidly clamped when the tube and rod are expanded by heat from the burning jet, and released for sliding 15 movement when the tube and rod contract upon cooling after said jet is extinguished whereby the cut-off valve may be retained in open position while the pilot is burning and released to a closed position when the 20 pilot becomes extinguished.

5. The combination with a gas burner, supply pipe, and gravity actuated cut-off valve mounted in the supply pipe for controlling the flow of gas therethrough to the 25 burner, of a pilot burner mounted adjacent the burner, said pilot burner comprising a tubular member; a cap secured upon one end of the tubular member and apertured to direct burning gas therefrom 30 over the burner; a rod extending through the tubular member; said rod being secured at one end upon the cap and extending outwardly through the opposite end of the tubular member in slidable engagement 35 therewith, the rod and tubular members made of metals adapted to cause a greater expansion of the tubular member than of the rod when heated by the burning jet; a slotted member slidably mounted upon the 40 rod adjacent the end of the tubular member and connected to the cut-off valve; a clamping member slidably and pivotally mounted

upon the rod adjacent the slotted member; nuts threaded onto the outer end of the rod for adjustably holding the clamping member in proximate relation to the slotted member; said slotted member being rigidly clamped when the tube and rod are expanded by heat from the burning jet, and released for sliding movement when the tube 45 and rod contract upon cooling after said jet is extinguished whereby the cut-off valve may be retained in open position while the pilot is burning and released to a closed position when the pilot becomes extinguished; and means for moving the clamping member to release the slide member. 50 55

6. The combination with a gas burner, supply pipe, and gravity actuated cut-off valve mounted in said supply pipe for controlling the flow for gas therethrough to the burner, of a pilot burner mounted adjacent the burner, and arranged to direct a pilot flame over the burner, said pilot burner comprising a tubular member; a rod 60 extending through said tubular member, said rod being secured within one end of the tubular member and extending outwardly in slidable engagement with the other end of the tube to permit relative movement 65 thereto due to a difference in the amount of expansion when the tube and rod are heated by a pilot flame; a retaining member mounted upon the outwardly extending end of the rod and connected to the valve, said retaining member being clamped in retaining 70 position to hold the valve when the rod and the tube are expanded by heat and released to permit closing of the valve when said members contract upon cooling. 75 80

In witness whereof I hereby set my signature.

GEORGE A. TUCK.
